UNITED STATES PATENT OFFICE.

GEORGE C. JORGENSEN, OF RED WING, MINNESOTA.

DESIGN FOR A BEDSTEAD.

Application filed December 10, 1927. Serial No. 24,443. Term of patent 3½ years.

To all whom it may concern:

Be it known that I, GEORGE C. JORGENSEN, a citizen of the United States, resident of Red Wing, county of Goodhue, and State of Minnesota, have invented a new, original, and ornamental Design for Bedsteads, of which the following is a specification, reference being had to the accompanying drawing, forming part thereof.

The figure shows a front perspective view illustrating my design.

I claim:

The ornamental design for a bedstead, as shown.

GEORGE C. JORGENSEN.
